UNITED STATES PATENT OFFICE.

DWIGHT THEODORE CLARK, OF EAST ORANGE, NEW JERSEY.

PUZZLE.

Application filed April 4, 1923. Serial No. 629,895.

To all whom it may concern:

Be it known that I, DWIGHT T. CLARK, a citizen of the United States, and a resident of East Orange, in the county of Essex and 5 State of New Jersey, have invented a new and Improved Puzzle, of which the following is a full, clear, and exact description.

This invention relates to improvements in amusement devices and has particular reference to a radio puzzle.

An object of the invention is to provide a puzzle in which a plurality of elements are manipulated until the same assume positions relative to each other which denote 10 a certain combination representing a code.

Another object is to provide a puzzle in which each of a plurality of elements may be moved about a common center and brought to rest in certain positions and in which skill 20 and dexterity is required in maintaining an element or elements in such positions while another element is being moved to a desired position.

A further object is the provision of a device 25 of the above character which is simple and inexpensive in construction and capable of affording considerable amusement and instruction to the user.

The above and other objects will appear 30 more clearly from the following detail description, when taken in connection with the accompanying drawing, which illustrates a preferred embodiment of the inventive idea.

In the drawing—

Figure 1 is a plan view of the puzzle constructed in accordance with the invention; and

Figure 2 is a section on the line 2—2 of Figure 1.

The embodiment of the present invention shown in the drawing comprises a casing 3 of rectangular formation, in the bottom of which is arranged a base 4 having an elevated portion 5 at one end thereof. On the portion 5 there is arranged an index 6 including a plurality of letters, all of which may be utilized to form certain code combinations designating various radio stations such as those indicated by the numeral 7 on the portion 4 of the base. The letters or characters forming the index 6 and the various stations with their respective codes may be printed or otherwise placed on the portions 5 and 4 of the base. Arranged adjacent the index 6 is a scale 8 having calibrations thereon, which scale may be utilized

in the working of the puzzle. In this event, the codes for the various stations would consist of figures instead of letters. It is to be understood, however, that the index including the letter characters is preferred.

Cooperating with the index 6 are a plurality of indicators or pointers 9, 10 and 11 of different lengths and having the common pivot 12 secured in the portion 5 of the base. The indicators or pointers are arranged on the pivot in superposed relation with respect to each other and each indicator is provided at one end thereof with a circular portion 13 having an opening 14 therein for receiving a ball 15 which engages the portion 4 of the base and is movable with the indicator when the same is manipulated about its pivot 12. The indicators 10 and 11 are bent, as indicated at 16 and 17, respectively, so that said indicators will not interfere with each other as the same are moved about the pivot 12.

The portion 4 of the base is provided with a plurality of rows of recesses or depressions, the recesses of the respective rows being designated by the numerals 18, 19 and 20. Each row is arranged concentrically with respect to the pivot 12 and associated, respectively, with the indicators 9, 10 and 11. The recesses in each row, by being arranged concentrically with respect to the pivot 12, are disposed in the path of movement of the ball 15 associated with the indicator with which said row cooperates, and will receive the ball therein as the indicator is moved about its pivot so that the indicator may be brought to rest in registration with certain of the characters in the index 6. The number of recesses in each of the rows is less than the number of characters in the index 6 so that the indicator associated with the particular row can only be retained in registration with certain of the characters in said index. Thus, when the casing 3 is manipulated to swing the various indicators about the pivot 12 by gravity, the indicator 9 can only be retained in registration with the characters H, S and J, the recesses in the row 18 being diametrically disposed with respect to these characters.

The portion of the base has mounted thereon a partition 21 forming compartments 22 for receiving the balls 15 when the puzzle is not in use.

In practice, it will be assumed for the purpose of illustration, that it is desired to manipulate the indicators to obtain the

code for the station designated St. Louis, Mo. The characters forming the code for this station are K, S and D. The user now manipulates the casing 3 from side to side 5 causing the various indicators to move about the pivot 12, such movement being facilitated by the weight of the balls 15 until one of the indicators can be brought to rest in registration with one of the letters of said 10 code, at which time the ball associated with said indicator will engage in one of the recesses of the row traversed by said ball. It then becomes necessary to bring each 15 of the remaining indicators into registration with one of the other characters of the code and at the same time so manipulate the casing that the indicator or indicators which have already been brought to rest in registration with other characters 20 will not be displaced by the tilting of the casing which, if excessive, will cause the ball 15 to be disengaged from a recess in which it is resting.

Although three indicators and three rows 25 of recesses have been shown, it will, of course, be understood that the number of indicators and rows of recesses is optional and need only correspond to the number of characters in the various codes.

30 What is claimed is:

1. In a puzzle, an index including a plurality of characters, a plurality of indicators movable with respect to said index and manipulated by gravity to register each 35 with a predetermined one of said characters, and means to retain each indicator in position after it has been registered with its associated character.

2. In a puzzle, an index including a plurality of characters, a plurality of indicators movable about a common center and with respect to said index to register each 40 with a predetermined one of said characters, and means to retain each indicator in position after it has been registered with its associated character.

3. In a puzzle, a base having a plurality 45 of recesses therein, an index on said base including characters, a plurality of indicators on said base, each of which is movable to register with one of said characters, and means movable with each indicator and engageable in one of said recesses when the associated indicator is in registration with 50 one of said characters.

4. In a puzzle, a base having a plurality 55 of rows of recesses therein, an index on said base including a plurality of characters, a plurality of indicators on said base,

each of said indicators being associated with 60 one of said rows of recesses and movable to register with one of said characters, and means movable with each indicator and engageable in a recess in the associated row when said indicator is in registration with 65 a predetermined one of said characters.

5. In a puzzle, a base having a plurality 70 of recesses therein, an index on said base including characters, a plurality of indicators on said base, each of which is movable to register with one of said characters, and a ball movable with each indicator and engageable in one of said recesses when said indicator is in registration with one of said characters. 75

6. In a puzzle, an index including a plurality of characters, a plurality of indicators of different lengths movable with respect to said index to register each with one of the characters thereon, a base on 80 which said indicators are movable and having a plurality of rows of recesses therein, each row being associated with one of said indicators, a common pivot on said base for said indicators and with respect 85 to which said rows of recesses are concentrically arranged, and means movable with each indicator and engageable in one of the recesses in the associated row when the indicator is in registration with one of said characters. 90

7. In a puzzle, an index including a plurality of characters, a plurality of indicators pivotally movable relative to said index to register each with one of said characters, and a base supporting said indicators and including means for releasably maintaining said indicators in registering positions. 95

8. In a puzzle, an index including a plurality of characters, a plurality of indicators movable about a common center and successively registrable each with one of said characters, and means for releasably maintaining each indicator in a registering position 100 during the registration of the succeeding indicators. 105

9. In a puzzle, an index including a plurality of characters, a plurality of pointers successively registrable each with a predetermined one of said characters, and means for releasably maintaining each pointer in a registering position during the registration of the succeeding pointers. 110
